LOUIS KELLNER, OF NEW YORK, N. Y.

DOUBLE-THROW SNAP-SWITCH.

1,354,761.

Specification of Letters Patent.

Patented Oct. 5, 1920.

Application filed March 28, 1918. Serial No. 285,805.

To all whom it may concern:

Be it known that I, LOUIS KELLNER, a citizen of the United States, and a resident of the borough of Manhattan, city, county, and State of New York, have invented certain new and useful Improvements in Double-Throw Snap-Switches, of which the following is a specification.

This invention relates to electric switches and, while the drawings illustrate a double-throw triple-pole switch, it will be obvious that the invention is equally applicable to switches having a single throw and to switches having any desired number of poles.

One of the objects of the invention is to provide simple, durable, and effective mechanism for operating the terminal bridging means with a rapid or snap action both to make and break the circuit.

A further important object of the invention is to provide a double-throw switch having a rocking terminal bridging brush formed of a plurality of resilient plates of conducting material adapted to make a firm and broad contact with either of two sets of line terminals.

Another object of the invention is to provide a switch having a rocking terminal bridging device and means embodying a single motor spring and switch handle for rocking said device with a snap action to close either of two circuits or to break both circuits.

35 A further object of the invention is to provide a switch having terminal bridging means, motor mechanism for shifting the bridging means with a snap action in opposite directions, means for automatically locking the bridging means in "on" and "off" positions, a swinging switch lever, and means controlled by said lever for storing power in the motor mechanism and subsequently releasing the bridging means to 40 permit the motor mechanism to snap the bridging means in a direction corresponding with the direction of movement of the lever.

In the drawings, Figure 1 is a vertical transverse sectional view of a triple-pole double-throw switch embodying the invention;

Fig. 2 a fragmentary vertical longitudinal sectional view on the line II--II of Fig. 3;

55 Fig. 3 a fragmentary horizontal section on the line III--III of Fig. 1;

Fig. 4 a detail side elevation of part of the operating mechanism;

Fig. 5 a fragmentary longitudinal section on the line V--V of Fig. 1, showing the parts in neutral position;

Fig. 6 a view similar to Fig. 5 showing the parts in position to close one of the circuits;

Fig. 7 a view similar to Fig. 5, a part of the mechanism being removed to more clearly show the locking mechanism;

Fig. 8 a fragmentary sectional view on the line VIII--VIII of Fig. 1; and Fig. 9 a vertical longitudinal section on the line IX--IX of Fig. 1.

The rocking contact brushes and the mechanism for operating the same are mounted in brackets 1 and 2 bolted or otherwise secured to one face of a base 3 of slate, porcelain or the like at opposite sides of said base. The three terminal-bridging contact brushes 4 are confined in a housing comprising the base plate 3, side walls or plates 5, intermediate partitions 6 similar to plates 5, and a top wall or plate 7. The plates 5, 6 and 7 and base plate 3 are rigidly connected together by bolts 10 which pass through the top and base plates and extend vertically through apertures in the plates 5 and 6.

The plates 5, 6 and 7 are formed of suitable insulating material and in conjunction with the base plate 3 form an insulating housing divided into three compartments, one for each brush 4 and its two associated pairs of line terminals 8 and 9. One terminal 8 is fixed to the base plate 3 adjacent one end of each compartment and their associated terminals 8 are mounted on the under side of the top plate 7 at the opposite ends of the compartments. One terminal 9 is fixed to the base plate in each compartment at the opposite end thereof from the lower terminal 8 and one terminal 9 is fixed to the under side of top plate 7 in each compartment at the opposite end of the compartment from the upper terminal 8.

The brushes 4 are formed of a plurality of leaves or plates of resilient conducting metal, the longest leaf being in the middle of the brush and the remaining leaves decreasing in length toward the top and bottom of the brush, as shown in Figs. 1 and 9. The brushes extend through apertures in a rocking bar 11 and are held to said bar by suitable bolts or rivets 12. The brushes are

insulated from the bar and the rivets 12 by blocks 13 of insulating material and by sleeves 14 of insulating material, shown in dotted lines in Figs. 1 and 9, embracing the shanks of the bolts or rivets. Any other suitable means of mounting and insulating the brushes on the bar 11 may be employed however. The bar 11 extends through circular apertures 15 in the plates 5 and 6 and 10 is formed at one end with a stub shaft 16 journaled in bracket 2 and at its opposite end with a shaft 17 journaled in the bracket 1. An upwardly extending plate 18 is formed on the bracket 1 adjacent the side 15 wall of the housing and said plate is provided with a large substantially circular opening 19 through the center of which the shaft 17 extends. A disk 20 held to one end of the bar 20 11 by suitable fastening devices 21 is adapted to oscillate or rotate in opposite directions in the opening 19 in plate 18 and said disk is normally held against rotation in either direction by two latch bolts 22 and 25 23 adapted to simultaneously engage opposite sides of either one of three lugs or 30 projections 24 formed on plate 18 and extending radially into the opening 19. The latch bolts 22 and 23 are slidably mounted in ways 30 25 and 26 formed in the outer face of disk 20 and are normally forced outwardly beyond the periphery of the disk by springs 27 and 28. A circular face plate 29 held to the outer face of disk 20 serves to slidably 35 confine the latch bolts in their guide-ways 25 and 26. A sleeve 30 is loosely mounted on shaft 17 to rotate about said shaft and a swinging switch lever 31 is rigidly connected with the outer end of the sleeve. A 40 motor spring 32 is coiled about the sleeve and the ends of said spring extend downwardly as shown in Figs. 1 and 8. The switch handle 31 is provided with a pin 33 which extends inwardly between the depending 45 free ends of the spring 32 and the disk 20 is provided with a pin 34 which extends outwardly between the depending ends of the spring. Sleeve 30 is formed with a flattened portion 30^a extending 50 through a similarly shaped aperture in an oscillating trip plate 35 said trip plate being thus held to oscillate in unison with the sleeve 30 and switch handle 31. The trip plate 35 is formed with a segmental slot 36 55 through which pin 34 extends to permit relative movement between the trip plate and the disk 20 and pin 34, and said plate is also provided adjacent its opposite edges with inwardly extending pins or projections 37 and 38 adapted to engage and elevate the outer ends of latch releasing levers 39 and 40 respectively. The releasing levers 39 and 40 are fulcrumed on pins 41 60 and 42, respectively, which extend through face plate 29 and into disk 29, and the in-

ner ends of said levers are formed with slots in which engage pins 43 and 44 fixed, respectively, on latch bolts 22 and 23. The face plate 29 is provided with slots 45 and 46 through which pins 43 and 44 extend. 70

With the parts in neutral position, as shown in Figs. 1, 5, 8 and 9, the brushes may be rocked toward the right or left to close either of the two circuits. To rock the brushes toward the right, the switch lever 31 is swung to the right, causing pin 33 to move relatively to pin 34 in a clockwise direction and thus placing motor spring 32 under tension. This movement of the switch lever also oscillates sleeve 30 and trip plate 35, thus causing pin 37 to move into engagement with the outer end of lever 39 and rock said lever about its pivot to draw latch bolt 22 inwardly into disk 20 from behind the central lug 24. The withdrawal of latch bolt 22 releases disk 20 and permits the motor spring to advance pin 34, thus rotating the disk and rocking the brush carrying bar 11 with a rapid snap action independently of further movement of the switch lever to the position shown in Fig. 6. This rapid movement of the disk relatively to the sleeve 30 and plate 35 carries the outer end of lever 39 away from pin 37, as shown in Fig. 6, and advances pin 34 85 until it is again along side pin 33. This movement of disk 20 and lever 39 permits spring 25 to project bolt 22 into the path of the right hand lug or stop 24 to arrest the parts in the position shown in Fig. 6, 100 with latch bolt 23 engaging the opposite side of said stop lug, thus locking the switch in "on" position against accidental movement in either direction. The outer sides of the latch bolts 22 and 23 are beveled or 105 rounded as shown to permit the foremost bolt to advance past the stop lugs during a movement of the switch mechanism in either direction. With the parts in the position just described the switch may be operated to break the circuit by moving the switch handle toward the left, causing pin 38 to operate lever 40 to release latch bolt 23, and it will be obvious that by advancing the switch lever a second time toward 115 the left the pin 38 will again operate lever 40 to release bolt 23 from the central stop 24 and permit the motor spring to rock the brushes from neutral position to a position closing the second circuit. 120

It will be observed that the trip pins 37 and 38 are so disposed relatively to releasing levers 39 and 40 that a substantial movement of the lever is required before the latch bolts can be released, thus rendering accidental operation of the switch practically impossible and insuring storing of considerable power in the motor spring before the latches are released. It will also be noted that by constructing the rocking 130

contact brushes 4 as described a firm and broad contact is insured between the brushes and the line terminals of both circuits, and that the latch bolts will lock the brushes with the ends of the leaves thereof pressed under tension on the terminals, the parts being so proportioned that the motor spring will rock the brushes a sufficient distance to cause the ends thereof to be deflected as indicated in dotted lines in Fig. 9 before the power of the spring is exhausted. It will be obvious that the forward latch bolt will prevent reverse rotation of the brush support and thus lock the brushes in engagement with the terminals while under compression.

If desired, plate 18 may be cut away at the lower portion of the opening 19 opposite the stops 24 to form a segmental recess 47 terminating in abutments or stop shoulders 48 adapted to be engaged by a stop lug 49 on disk 20 to limit the extent of rotation of the disk and insure engagement of the latch bolts with the two end stops 24 even if the latch bolts should become somewhat sluggish in operation. A spring-pressed retarding plunger 50 may be held to plate 18 midway of the segmental recess 47 to engage the lug 49 on disk 20 and thus retard the final movement of the disk to neutral position from either "on" position. The stop lug 49, recess 47 and plunger 50 are not essential however, and may be omitted.

What I claim is:

35 1. An electric switch comprising two sets of oppositely arranged diagonally disposed line terminals wired for two circuits, a terminal bridging device having a neutral position and two oppositely inclined "on" positions, a rocking support for said device, a single motor spring, a switch handle, means controlled by the switch handle for storing power in said spring to rock said support with a snap action in either direction, means 40 for automatically locking said support against movement in either of its three positions, and means controlled by the switch handle for releasing said latching means at the conclusion of the power storing movement of the switch handle.

2. In an electric switch, the combination of terminal bridging means rotatable in opposite directions, fixed stops spaced apart, a pair of latches rotatable with the bridging means adapted to engage opposite sides of each of said stops to lock the bridging means against rotation in either direction, a switch handle, a motor spring, connections between said spring and the handle and bridging means for storing power in said spring to rotate the bridging means in either direction, and latch tripping means operable by the handle adapted to trip one of said latches after a power storing movement of the handle in one direction and to trip the other of

said latches after a power storing movement of the handle in another direction.

3. In an electric switch, the combination of terminal-bridging means rotatable in opposite directions, fixed stops spaced apart, a pair of latches rotatable with the bridging means adapted to engage opposite sides of each of said stops to lock the bridging means against rotation in either direction, a coiled motor spring having projecting ends, a rotatable switch handle, arms rotatable with the handle and bridging means extending between the ends of said spring, and latch tripping means rotatable with the handle adapted to release either of said latches after a power storing movement of the handle.

4. In an electric switch, the combination of diagonally disposed line terminals, rocking terminal bridging means, an element rotatable in opposite directions operatively connected to rock the bridging means, spaced stops, a pair of latches carried by said element adapted to automatically engage opposite sides of either of said stops to lock said element against movement in either direction, a coiled motor spring having projecting ends, a pin carried by said element extending between the ends of the spring, a switch handle, a pin carried by the switch handle extending between the ends of the spring and means controlled by the handle for withdrawing either of said latches from engagement with a stop.

5. In an electric switch, the combination of diagonally disposed line terminals, rocking terminal bridging means, an element rotatable in opposite directions operatively connected to rock the bridging means, spaced stops, a pair of latches carried by said element adapted to automatically engage opposite sides of either of said stops to lock said element against movement in either direction, a coiled motor spring having projecting ends, a pin carried by said element extending between the ends of the spring, a switch handle, a pin carried by the switch handle extending between the ends of the spring, a pair of releasing levers pivoted on the rotatable element and each connected at its inner end with one of said latches, and means controlled by the handle for rocking either of said levers about its pivot to release its connected latch.

6. In a switch, the combination of line terminals, terminal bridging means, a rotatable member connected to shift said bridging means, a plurality of stops, a pair of spring pressed latch bolts carried by said member adapted to engage opposite sides of either of said stops, a pair of levers carried by said member each operatively connected to retract one of said latch bolts, a motor spring having projecting ends, a pin carried by said member extending between the ends of the spring, a switch handle, a pin carried

- by said handle extending between the ends of the spring, and a trip device operable by said handle adapted to operate one of said levers when the handle is moved in one direction and to operate the other lever when the handle is moved in the opposite direction.
7. A double-throw switch having two pairs of diagonally disposed fixed contacts, a conducting device adapted to connect the contacts of either pair and having an intermediate neutral position, rocking means supporting said conducting device intermediate its ends, a rotatable disk fixed to said rocking means, three fixed stops spaced apart about the periphery of said disk, a pair of reciprocable spring pressed latch bolts normally projecting beyond the periphery of the disk and adapted to engage opposite sides of either of said stops to hold the disk against movement in either of its three positions, a pair of releasing levers fulcrumed on said disk and connected at their inner ends with the latch bolts, a switch handle, a trip plate shiftable by said handle and having two spaced projections each adapted to engage one of said levers when the handle is moved, and means controlled by said handle for rotating the disk in the direction of movement of the handle when the handle is shifted sufficiently to retract either of said latch bolts.
8. In a multiple-throw electric switch, the combination of stationary contacts, contact-bridging means, a rotatable member connected to shift the bridging means in either direction, a plurality of spaced stops, a pair of latch bolts carried by said member adapted to engage opposite sides of either of said stops, a motor spring, an operating handle capable of rotary movement in either direction, connections between said spring and the handle and rotatable member for storing power in the spring to rotate said member in the direction of movement of the handle, and means operable by said handle for releasing one of said latch bolts when the handle is rotated in one direction and for releasing the other bolt when the handle is rotated in the opposite direction.
9. In a multiple-throw electric switch, the combination of stationary contacts, contact-bridging means, a rotatable member connected to rotate the bridging means in either direction, a plurality of spaced stops, a pair of latch bolts carried by said member adapted to engage opposite sides of either stop, a releasing device for each bolt carried by said member, a motor spring, an operating handle rotatable in either direction, connections between said spring and the handle and member for storing power in the spring to rotate said member in the direction of movement of the handle, and means rotatable with the handle for actuating one of said bolt-releasing devices when the handle is moved in one direction and for actuating the other device when the handle is moved in the opposite direction.
10. In a multiple-throw switch, the combination of stationary and movable contacts, a rotatable element for rotating the movable contacts, a plurality of spaced stops, devices carried by said element adapted to engage opposite sides of either stop, a releasing lever for each device pivoted on said element, a motor spring, a rotatable operating handle, connections between the spring and said handle and element for storing power in the spring during an initial movement of the handle in either direction, and spaced trips rotatable with the handle each of which is adapted to actuate one of said releasing levers after a predetermined movement of the handle.

In testimony whereof I hereunto affix my signature.

LOUIS KELLNER.
